UNITED STATES PATENT OFFICE.

CARL A. FRAHM AND JULIUS H. SCHLAFLY, OF CANTON, OHIO, ASSIGNEES, BY MESNE ASSIGNMENTS, TO THE BERGER MANUFACTURING COMPANY, OF CANTON, OHIO, A CORPORATION OF OHIO.

CHANNEL-FORMING MACHINE.

Application filed May 28, 1924. Serial No. 716,396.

The invention relates to a machine for making channels with edge flanges from steel strips, for use in building construction as sills, joist, studs, and the like; and the object of the improvement is to provide differential rolls with centering feeding guides and straightening delivery rolls for producing a flanged channel directly from a strip of sheet steel by a continuous operation, and especially to provide lateral adjusting means for certain rolls, for producing channels with webs and flanges of different widths and depths upon the same machine, without removing or replacing any portion thereof.

The invention is illustrated in the accompanying drawings, forming part hereof, in which:

Fig. 1 is a side elevation, in two sections, of the entire machine, omitting certain portions of the driving gearing;

Fig. 2, a plan view of the forward portion of the machine, with the housings and the gearings and rolls removed, to show the stationary and adjustable bases;

Fig. 2', a like view of the rear portion of the machine;

Fig. 2^a, a fragmentary section, as on line 2^a—2^a, Fig. 2, showing a base adjusting guide;

Fig. 3, a series of sections of steel strips of different widths, showing the initial bending of edge flanges to form channels of different widths and depths;

Fig. 4, a series of similar sections, showing edge flanges completely formed thereon and the initial bending of channel flanges to form channels of different widths and depths;

Fig. 5, is a cross section of the guiding feed table on line 5—5, Figs. 1 and 2, showing therein a steel strip of the greatest width usually employed;

Fig. 5^a, an enlargement of the guide adjusting rod and sleeve shown in Fig. 5;

Fig. 6, a front end view of the channel forming machine, showing the feed and flattening rolls and the housings and gearings in elevation, with a steel strip in section of the greatest width usually employed; and showing in section, as on line 6—6, Figs. 1 and 2, the right side adjusting means;

Fig. 7, a cross section, as on line 7—7, Figs. 1 and 2, of the initial edge-flange bending rolls, bearings and housings, and the

left side adjusting means, showing the driving gearing in front elevation;

Fig. 7^a, an enlargement of the steel strip section with the initial bending of edge flanges, shown in Fig. 7;

Fig. 8, a cross section, as on line 8—8, Figs. 1 and 2, of the second edge-flange bending rolls, bearings, housings and bases, showing the rolls and driving gearings in front elevation;

Fig. 8^a, an enlargement of the steel strip with the second bending of edge flanges, shown in Fig. 8;

Fig. 9, a cross section, as on line 9—9, Figs. 1 and 2, of the housings, bearings and left side adjusting means showing in front elevation the final bending rolls for the right side edge flange;

Fig. 9^a, an enlargement of the steel strip section with the final bending of a right edge flange, shown in Fig. 9;

Fig. 10, a cross section, as on line 10—10, Figs. 1 and 2, of the housings, bearings and left side adjusting means, showing in front elevation the final bending rolls for a left side edge flange;

Fig. 10^a, an enlargement of the steel strip section with the final bending of a left edge flange, shown in Fig. 10;

Fig. 11, a fragmentary section, as on line 11—11, Figs. 9 and 10, showing a side elevation of the final bending rolls for the edge flanges;

Fig. 12, a cross-section, as on line 12—12, Figs. 1 and 2, of the initial bending rolls for channel flanges, showing the bearings, housings and left side adjusting means;

Fig. 12^a, an enlargement of the sheet strip section with the initial bending of channel flanges, shown in Fig. 12;

Fig. 13, a cross-section, as on line 13—13, Figs. 1 and 2, of the bearings and housings, showing in front elevation the second bending rolls for channel flanges;

Fig. 13^a, an enlargement of the steel strip section with the second bending of channel flanges, shown in Fig. 13;

Fig. 14, a cross-section as on line 14—14, Figs. 1 and 2 of the bearings and housings, showing in front elevation the third bending rolls for the channel flanges;

Fig. 14^a, an enlargement of the steel strip section with the third bending of channel flanges, shown in Fig. 14;

Fig. 15, a cross-section, as on line 15—15, Figs. 1 and 2, of the housings, and bearings, showing in front elevation the fourth bending rolls of a left side channel flange;

5 Fig. 15^a, an enlargement of the steel strip section with the fourth bending of a left channel flange, shown in Fig. 15;

Fig. 16, a cross-section, as on line 16—16, Figs. 1 and 2, of the housings and bearings, 10 showing in front elevation the fourth bending rolls for a right side channel flange;

Fig. 16^a, an enlargement of the steel strip section with the fourth bending of a right channel flange, shown in Fig. 16;

15 Fig. 17, a cross-section, as on line 17—17, Figs. 1 and 2, of the housings and bearings, showing in front elevation the final rolls for a left side channel flange;

20 Fig. 17^a, is an enlargement of the steel strip section with the final bending of a left side channel flange, shown in Fig. 17;

Fig. 18, a cross-section, as on line 18—18, Figs. 1 and 2, of the housings and bearings, 25 showing in front elevation the final bending rolls for a right side channel flange;

Fig. 18^a, is an enlargement of the steel strip section with the final bending of a right side channel flange;

30 Fig. 19, a cross-section, as on line 19—19, Figs. 1 and 2, of the bases, showing in front elevation the web flattening and delivery rolls and the bearings and housings therefor, and the channel straightening rolls beyond the same;

35 Fig. 20, a perspective view of a completely formed channel; and

Fig. 21, a fragmentary section of two channels with their webs abutted and joined together, as by rivets or spot welding, to

40 form a steel joist.

Similar numerals refer to similar parts throughout the drawings.

The steel strips to be formed into channels are finished to the proper width and 45 cut to the proper length for making the desired product, and when the same are made from sheets they are slit to form strips having a sufficient width to include the web, the channel flanges, and the edge flanges of the 50 channel to be formed.

The forming of channels from strips involves a bending of the metal at the angles of the flanges, and the machine embodying the present improvement is designed upon 55 an assumed base line along the angle to be bent between the web and the right side channel flange, as shown by heavy broken lines $w-w$ traversing the sections shown in Figs. 3 and 4. For this reason the rolls employed for bending the strip to form this 60 angle require no lateral adjustment, and the same are mounted in bearings in housings which are fixed upon the base of the machine.

The width of the channel flange, however,

necessarily varies in the formation of channels of different depths, as shown by light broken lines $y-y$ traversing the sections shown in Fig. 3 of the drawings; which necessitates a lateral adjustment of the rolls 70 employed for bending the angles between the channel flanges and the edge flanges, on each side of the assumed base line of the machine.

Furthermore, the width of the web necessarily varies in the formation of channels of different widths, as shown by light broken lines $z-z$ traversing the sections shown in Fig. 4 of the drawings; and for this reason the rolls employed for bending the angle between the web and the left side channel flange, require a lateral adjustment with respect to the assumed base line of the machine, which corresponds to the location of the rolls employed for bending the angle between the web and the right side channel flange; the reference to right and left side being with respect to one facing the front end of the machine and looking toward the rear end thereof.

And finally, the varying width of the strips used for making channels of different widths and depths, requires not only a lateral adjustment of the guides on the feed table with respect to each other, but also 95 requires a lateral adjustment of the right side guide, so as to properly direct the strip into the forming machine for bending the angle of the right side edge flange at the proper distance from the angle to be bent in forming the right side channel flange, as indicated by the heavy and light broken lines in Fig. 3 of the drawings.

The feed table.

The feed table 22 may be mounted on corner standards 23 upon a base 24 secured by bolts 25 to the forward end of the stationary base 26 of the channel forming machine; and upon the top of the table are 110 provided a plurality of transverse dove-tailed channels 27, which receive and guide transverse dove-tailed slides 28 formed or secured on the bottom of the longitudinal guide plates 29 which plates rest and may 115 slide laterally upon the top of the table.

A wearing plate 30 is preferably secured upon each guide plate 29 as by screws 31, and aligned guide bars 32 and 32' are secured upon the outer side of each wearing plate by means of bolts 33 extending through slotted apertures 34 in the guide bars 32 and through the wearing plates into the guide plates, so that the guide bars may be given a slight lateral adjustment thereon.

A guide roll 35 is mounted on each guide plate in the forward part of the table between the adjacent ends of the aligned guide bars 32 and 32'; and a guide roll 35' is mounted on the rear end of each guide plate 130

at the end of the guide bar 32. The guide rolls are mounted for turning on vertical axes, and the roll 35 may be cylindrical in form with a conical flange on its lower end 5 for acting on the edges of a steel strip A to center the same between the guide bars, while the rolls 35' may be provided with reversely coned flanges forming a groove 35'' for centering and guiding the strip in the 10 proper plane for entering between the nip of the feeding and flattening rolls 36 of the forming machine.

The guide bars are adjusted approximately to the width of the strip, while the 15 guide rolls are adjusted more exactly thereto, so that the rolls will not only accurately center the strip but will direct it longitudinally into the channel forming machine in proper position for the operation of the series of bending rolls.

A number of transverse channels 38, located a substantial distance apart, are provided in the top of the table, in each of which is located an adjusting screw rod 39 25 or 39' and a reverse screw sleeve 39^a swivelled on one end thereof; and bearing plates 40 and 40' are secured to the sides of the table, in which the end portions of the rod and sleeve respectively are journaled, suitable collars 41 being provided on the rod 30 and a collar flange 41' being provided on the sleeve to stop the same from endwise movement.

Screw bearing lugs 42 and 42' are formed 35 on or secured to the longitudinal plates 29 and depend into the transverse channel 38 for operating engagement with the screw rods and swivelled sleeves respectively, by means of which the guide plates and the 40 guide members thereon may be adjusted laterally upon the table. A squared shank 39'' is provided at each end of at least one of the screw rods, by means of which the same can be turned by a crank 43 applied 45 to either end thereof.

A chain gear 44 connects the ends of the rods on one side of the machine, and a chain gear 44' connects the ends of the sleeve on the other side of the table, so that they will 50 be rotated in unison.

A tubular extension 39^{a'} is provided on the outer end of one of the sleeves around the screw rod. This sleeve is provided with a plurality of longitudinally slits 39^{a''}, and is 55 surrounded by a split band 45 provided with radial flanges 45', by means of which the tubular extension of the sleeve may be clamped upon the rod by a bolt 45'' to rotate the one by the other.

60 When it is desired to adjust the guides on the feed table for a strip of any particular width, the band 45 is clamped by the bolt 45'' around the tubular extension 39^{a'} of the sleeve to co-ordinate the movements of the 65 guide bars on both sides, and the rod and

sleeve are then rotated together by the crank 43 on one rod, to adjust the right side guide bars and rolls laterally into proper position to direct the right edge of the strip into the channel forming machine for forming the right side flanges of the channel for which the strip is intended; whereupon the swiveled sleeve is released from the rod by unscrewing the bolt 45'', whereupon the left side guide bar and rolls are laterally adjusted for the left edge of the strip, by rotating the screw rod by the crank without turning the sleeve swiveled thereon; after which the sleeve is again clamped to the rod, and the guides can then be adjusted to and from each other to accommodate slight variations in the widths of strips.

The channel forming machine.

Upon the main stationary base 26 of the 85 channel forming machine, are mounted a number of movable bases 46, 46^a and 46^b for supporting the housings and bearings for the rolls requiring a lateral adjustment, and protruding from the bottom at each end of 90 each movable base is provided a flange 47 which is adapted to engage under the overlapping flange of a guide bar 47', or 47'', under which the base flanges may slide during a lateral adjustment of the movable 95 bases. These guide bars are secured to the stationary base by means of bolts 47''', and some of the guide bars 47'' may be proportioned so that they may be clamped upon the base flanges, for holding the movable bases 100 firmly upon the stationary base, as shown in detail in Fig. 2^a.

The adjustable base 46 is L-shaped in plan form and upon the forward longitudinal stem portion thereof is mounted the housing 48 which carries the bearings 49 for the corresponding journal ends of shafts 36' of the feeding and flattening rolls 36, the bearings 49' for the corresponding journal ends of the shafts 50'' of the rolls 50 and 50' used for 105 initially bending the right edge flange a of a strip, and the corresponding journal ends of the shafts 51'' of the rolls 51 and 51' used for the second bending of the right side edge flange a'; and upon the transverse rear L portion 46' of the movable base 46 is 110 mounted the housing 52 which carries the bearings 53, and 54 for the rolls 55, 55' and 56, respectively, which are used for finally bending the right side edge flange a'' of a 115 strip.

A screw bearing 57 is secured in each end of the movable base 46, in each of which bearings is operatively engaged a screw rod 58 or 58', which rods extend to the left through journal bearings 59 mounted on brackets 60 secured to the left side of the stationary base, with end thrust collars 61 held in place by adjustable lock nuts 62 on 120 the bar at each side of the bearings for hold-

ing the rods from endwise movement; and a chain gearing 63 is operatively mounted on the ends of these rods for rotating them in unison by a crank on the protruding square shank end 58" of either one of the rods.

By these means, the movable base 46 and the housings thereon with all the journal bearings carried thereby, may be bodily adjusted laterally of the forming machine, and the corresponding shafts are carried endwise with the bearings by the abutment of the hubs of the several rolls on the inner end and of a stop collar 64 on the outer end thereof; so that all these parts may be bodily adjusted laterally by a turning of the screw bars 58 and 58' by a crank on the end of either one of them, for bringing all the rolls which are successively used for bending the right side edge flange a'' of a strip, into proper position for their particular work.

The maximum variation in the depth of a channel, and the corresponding width of the channel flanges, does not ordinarily exceed two or three inches, so that the feeding and flattening rolls and the right side edge bending rolls do not require any greater adjustment than this variation; and to accommodate such an adjustment the individual gear wheels 65 and the master gear wheel 66 are driven by pinions 65' and 66' having their faces wide enough to accommodate the lateral adjustment of the gear wheels without any corresponding movement of the pinions. The bearings 65^a for the journals on the inner ends of the shafts 65" of the individual pinions 65' are mounted in the movable housing 48, and are free to move along these shafts during a lateral adjustment of this housing.

A stationary housing 48^a is secured on the left forward corner of the stationary base and carries the bearings 36' for the corresponding journal ends of shafts of the feeding and flattening rolls 36; and these journals on the left end of the shaft 36 are free to slide endwise in the bearings during a lateral adjustment of the rolls, which are made long enough to include the widest strip for which the channel forming machine is designed, when the rolls are adjusted to the extreme right side position, as shown in Fig. 6.

The adjustable base 46^a is likewise L-shaped in plan form, and the rear transverse L-portion 46^{a'} is spaced from and connected with the forward longitudinally extending stem portion thereof by a flanged yoke 46^{a''}, for receiving between them the transverse rear L-portion 46' of the movable base 46 when these bases are moved toward each other to adjust the forming rolls for making the narrower channels.

Upon the forward longitudinal stem portion of the movable base 46^a is mounted the housing 48^a which carries the bearings 49^{a'}

for the corresponding ends of the shafts 50' of the rolls 50 and 50' used for initially bending the left edge of a strip a , and the corresponding ends of the shafts 51" of the rolls 51 and 51' used for the second bending 70 of the left side edge a' ; and upon the transverse rear L-portion 46^{a'} of the movable base 46^a is mounted the housing 52^a which carries the bearings 53^a and 54^a for the rolls 55^a, 55^{a'} and 56^a respectively, which are used for 75 finally bending the left side edge flange a'' .

A screw bearing 57^a is secured in each end of the movable base 46, in which bearing screw rods 58^a or 58^{a'} are operatively engaged. These rods extend to the left 80 through journal 59^a mounted on brackets 60^a secured to the left side of the stationary base, with end thrust collars 61^a held in place by adjustable lock nuts 62^a on the rod at each side of the bearings, for holding the rods 85 from endwise movement; and a chain bearing 63^a is operatively mounted on the ends of these rods for rotating them in unison by a crank on the protruding square shank end 58" of either one of these rods.

By these means, the movable base 46^a and the housings thereon, with all the journal bearings carried thereby, may be bodily adjusted laterally of the forming machine 90 for bringing all the rolls successively used for bending the left edge flanges a'' of a strip; and to permit this adjustment, the hubs of the left side rolls 50^a and 50'^a, and 51^a and 51'^a are splined upon the shaft 50" and 51" so as to slide endwise thereon, and these hubs are extended along the shafts to form journal sleeves 50^{a'''} and 51^{a'''} respectively for turning in the bearings 49^{a'} and 49^{a''}; the journal sleeves being stopped from 95 endwise movement in the bearings by the abutment of the roller hubs on one end and the abutment of a stop collar 64^a on the other end thereof.

The final bending rolls for each edge flange a'' of a strip, include a pair of cylindric rolls 110 55 or 55^a turning on axes at right angles to each other which are journaled in a bracket 53 or 53^a, for bearing against the under side and the outer side respectively of the strip and the formed edge flange; and a V-face 115 disk wheel 56 or 56^a turning on an inclined axis journaled in a bearing 54 or 54^a, for operating on the inner sides of the angles opposite the ends of the under and outer rolls, to finally form the edge flange at an 120 exact right angle to the body A of the strip, as shown in Figs. 9 and 10.

The bearing brackets 53 and 53^a are each provided with transverse slide flanges 53' bearing in transverse slide ways 67' formed in a supporting base 67 secured in the housing 52 or 52^a. A screw rod 68 is journaled in a bearing 68' in the side wall of the housing, with stop collars 68" on each side thereof, and is operatively engaged in a screw bear-

ing 53" formed on or secured to the bearing bracket for adjusting the cylindric rolls together laterally in the respective housings so as to accurately position them for their particular work.

The bearing brackets 54 and 54^a for the V-face rolls 56 and 56^a, are provided with transverse slide flanges 54' bearing in transverse slide ways 69' formed in a supporting bracket 69 depending from and secured to the top of the housing 52 or 52^a by bolts 69". A screw rod 68^a is journaled in a bearing 68^a' in the side wall of the housing, with stop collars 68^a" on each side thereof, and is operatively engaged in a screw bearing 54" formed or secured on the bearing bracket for adjusting the V-face roll laterally in housing, so as to accurately position the same for its particular work.

The upper face of the upper wall 68^b of the supporting bracket is formed in a downwardly diverging plane from the opposing underside face of the top wall 52^b of the housing, and a wedge plate 70 is interposed between these faces, between which it is endwise movable by means of a screw rod 70^a secured to the housing and extending through L-flange 70' on the free end of the wedge plate with a nut 70^a' on each side thereof, for adjusting the supporting bracket and V-face roll upward and downward within the housing, to accurately position the same for its particular work.

It will be understood that the bolts 69" are loosened before a lateral or a vertical adjustment is made for the supporting bracket 69 and that these bolts may be tightened after an adjustment is made; and it will also be understood that the described lateral adjustments which may be given to the cylindric rolls 55, and the lateral and vertical adjustments which may be given to the V-face rolls 56, may be made independently of each other, as well as of the lateral adjustment which may be given to all of these rolls together by the movable bases 46 and 46^a upon which their respective housings are mounted; so that these rolls can not only be adjusted together into proper position for bending an edge flange into proper width, but can be adjusted independently for properly cooperating in the final formation of the channel flange at an accurate right angle from the web A' of the strip.

A stationary housing 48' is fixed upon a seat 46' formed or secured upon the stationary base 26; which housing carries the bearings 49" for the shafts 71", 72" and 73" for the rolls 71 and 71', 72 and 72' and 73 and 73' used for the first, second and third bending of the right channel flange b', for which no lateral adjustment of these rolls is required because the angle of this flange is the assumed base line upon which the

stationary or non-adjustable parts of the machine is built.

Likewise, stationary housings 52' and 52" are fixed upon seats 46" formed or secured upon the stationary base 26; which housings 70 carry the bearing brackets 53^c and 53, for the cylindric rolls 55, and the bearing brackets 54^c and 54 for the V-face rolls 56, which are used for the fourth and for the fifth and final bending of the right side 75 channel flange b" of a strip, which rolls are mounted in their respective housings for the same lateral and vertical adjustments which have been described for the like rolls which have been used in finally bending the edge flanges.

The adjustable base 46^b, is L-shaped like the adjustable base 46^a, except that its forward longitudinal portion is somewhat longer and that it is provided with two rear transverse portions 46^b', which are spaced apart and connected together by a flanged yoke 46^b" for receiving between them the forward seat portion 46' of the stationary base upon which the housing 52' in which the fourth right side channel bending rolls are mounted.

Upon the forward longitudinal stem portion of the movable base 46^b is mounted the housing 48^b, which carries the bearings 49^a" for the journal sleeves 71^a", 72^a" and 73^a" on the ends of the hubs of the corresponding rolls used for the first three bendings of the left channel flange b' of a strip, which hubs and sleeves are splined upon the shafts 71", 72" and 73" to permit an endwise sliding adjustment thereon; and upon the transverse rear L-portions 46^b' of the movable base 46^b, are mounted the housings 52^a' and 52^a" which carry the bearings 53^b, for the cylindric rolls 55^a and 55^a' and the bearings 54^a for the V-face rolls 56^a which are used for the fourth and the final bending of the left side channel flange b", which rolls are provided with the same means for lateral and vertical adjustment within their housings, described for the corresponding rolls in finally bending the edge flanges.

A screw bearing 57^b is secured in each end of the movable base 46^b, in each of which bearings is operatively engaged a screw rod 58^b, which rod extends to the left through journal bearings 59^b mounted on brackets 60^b secured to the left side of the stationary base with end thrust collars 61^b held in place by adjustable lock nuts 62^b at each side of the bearings, for holding the rods from endwise movement; and a chain bearing 63^b is operatively mounted on the ends of these rods for rotating them in unison on the square shank end 58^b' of either one of the rods.

By these means, the movable base 48^b and the housing thereon with the journal bearings carried thereby, may be bodily adjusted

laterally of the forming machine for bringing all the rolls used successively for completely bending the channel flange b'' of a strip; and the right channel flange b'' having been completely formed by the right side rolls as described, the fully formed channel is delivered to the flattening rolls 74, shown in Fig. 19.

The flattening rolls are keyed on shafts 10 74" journaled in bearings 49" carried in housings 48" fixed on seats 46" formed or secured on the rear end of the stationary base 26. The lower flattening roll 74 is cylindric in form and of sufficient length to 15 form a bearing for the entire width of the widest channel for which the forming machine is designed; and the upper flattening rolls 74 may be in the form of two spaced disks splined on their shaft for lateral adjustment with set screws 75 for holding them in a given position. These disk rolls are intended to bear upon the web c of a 20 formed channel A'' intermediate the flanges thereof, so as to flatten any transverse curvature there may be therein.

The straightening rolls 76, each having a peripheral flange 76' on the outer side of the body portion, are mounted on a shaft 76" journaled in bearings 49" carried by the 30 housing 48" in rear of the flattening rolls; and the hubs of these rolls are splined on the shaft to permit an endwise adjustment thereon and are provided with set screws 77 for securing them in a given position of 35 adjustment.

The flanges of the straightening rolls engage the outer sides of the channel flanges b'' to hold them in alignment while the treads formed by the peripheries of the body 40 portions of the rolls 76 bear upon the in-turned edge flanges a'' for the purpose of deflecting the formed channel downward in front of the fulcrum formed by the lower straightening rolls 74, so as to straighten out 45 the upward curvature or chamber which is given to the channel by the action of the rolls in forming the flanges, thereby delivering the channel from the forming machine in a true flat straight condition throughout its 50 length and breadth.

An edge guide roll 78 may be mounted on a supporting guide bar 79 for the partly formed strip A' opposite each set of flange forming cylindric rolls 55 or 55^a, and these 55 guide bars may extend to and be supported by the adjacent housing so as to be laterally adjusted by the movable housings for the differential channel widths; and laterally extending guage-bars 80, 80', 80^a and 80'^a provided with suitable scales may be secured to the stationary and movable bases so as to cooperate one with the other for indicating the lateral adjustment of the movable bases upon the stationary base.

65 Furthermore, the tread portions of the

forming rolls 50 and 50', and 50^a and 50'^a, et seq., may be detachably secured to the of the rolls, as by bolts 81 clamping the sides of aligned flanges 81', which may be rabbed as at 81''' as shown in Fig. 7 so that the 70 tread portions of worn rolls can be readily removed for replacement without a renewal of the entire roll structure.

Finally, it will be understood that the use of the forming machine illustrated and described herein, is not limited to the shaping of a channel section; for the same mechanisms can be employed to form various sections from a strip of steel by merely modifying the shape and arrangement of the various rolls.

We claim:

1. A feed table for a channel-forming machine or the like, including a longitudinal guide on each side of the table, each guide including a plurality of guide rolls for side engagement with the longitudinal edge of a sheet passing over the feed table, one roll on each side being cylindric with a conical flange and another having a groove formed by conical flanges.

2. A feed table for a channel-forming machine or the like, including a longitudinal guide on each side of the table, each guide including two guide bars and a plurality of 95 guide rolls, one roll in each side being located between adjacent ends of the guide bars and being cylindric with a conical flange and another roll having a groove formed by conical flanges.

3. A feed table for a channel-forming machine or the like, including a longitudinal guide on each side of the table, and co-ordinated means for alternately adjusting laterally both of the guides together and one 105 of the guides separately.

4. A feed table for a channel-forming machine or the like, including a longitudinal guide on each side of the table slidable laterally thereon, there being a screw bearing in each guide, a transverse screw rod swiveled in the table operating in one screw bearing, and a screw sleeve swiveled on the screw rod operating in the other screw bearing.

5. A feed table for a channel-forming machine or the like, including a longitudinal guide on each side of the table slidable laterally thereon, there being a screw bearing in each guide, a transverse screw rod 120 swiveled in the table operating in one screw bearing, a screw sleeve swiveled on the screw rod operating in the other screw bearing, and means for clamping the swiveled sleeve to the screw rod.

6. A feed table for a channel-forming machine or the like, including a longitudinal guide on each side of the table slidable laterally thereon, there being a plurality of screw bearings in each guide, a plurality of 130

- transverse screw rods swiveled in the table operating in the screw bearings of one guide, screw sleeves swiveled on the screw rods operating in the screw bearings of the other guide, means for clamping the swiveled sleeves to the screw rods, a gearing connection between the screw rods, and a gearing connection between the swiveled sleeves. 5
7. A forming machine including a series of forming rolls in each side of the machine, and separate means for laterally adjusting in unison inward and outward the entire series of rolls in each side of the machine independently of the series of rolls in the other side of the machine. 10
8. A forming machine including a series of forming rolls in each side of the machine and flattening feed rolls in front thereof, means for adjusting the flattening feed rolls 20 and the series of forming rolls in one side laterally of the machine, and separate means for adjusting the forming rolls on the other side laterally of the machine. 25
9. A forming machine including a bearing mounted on each side, a shaft having one end journaled and stopped from endwise movement in one bearing, a forming roll fixed on the shaft adjacent to the one bearing, a forming roll splined on the shaft adjacent to the other bearing, there being a hub sleeve extending from the splined roll journaled and stopped from endwise movement in the other bearing. 30
10. A forming machine including a stationary base, a laterally movable base on each side thereof, a housing on each movable base, a series of bearings in each housing, a series of shafts having one end journaled and stopped from endwise movement in the 35 bearings in one housing, a series of forming rolls fixed on the shafts adjacent to the one housing, a series of forming rolls splined on the other ends of the shafts, there being hub sleeves extending from the splined rolls journaled and stopped from endwise movement in the bearings in the other housing. 40
11. A forming machine including a base, a housing on each side of the base, one of the housings being laterally movable on the base, a series of bearings in each housing, a series of shafts, each having one end journaled and stopped from endwise movement in the bearings in the other housing, a series of forming rolls fixed on the shafts adjacent to said other housing, a series of forming rolls splined on the other ends of the shafts, there being hub sleeves extending from the splined rolls journaled and stopped from endwise movement in the bearings in the one housing. 55
12. A forming machine including a stationary base with transverse guides thereon, a movable base having a screw bearing in each end and having transverse flanges slidably engaging the guides, a transverse screw rod journaled and stopped from endwise movement in the base at each end of the movable base and operating in the screw bearings, and gearing connections between the screw rods for turning the same in unison 70 to bodily adjust the movable base laterally upon the stationary base. 75
13. A forming machine including a stationary base, a housing thereon, a forming roll journaled in the housing, a bearing bracket mounted in the housing, a forming roll journaled in the bearing bracket, and means for laterally adjusting the bearing bracket in the housing. 80
14. A forming machine including a stationary base, a laterally adjustable housing thereon, a forming roll journaled in the housing a bearing bracket mounted in the housing, a forming roll journaled in the bearing bracket, and means for laterally adjusting the bearing bracket in the housing. 85
15. A forming machine including a stationary base, a housing thereon, a forming roll journaled in the housing a bearing bracket mounted in the housing, a forming roll journaled in the bearing bracket, and means for vertically adjusting the bearing bracket in the housing. 90
16. A forming machine including a stationary base, a laterally adjustable housing thereon, a forming roll journaled in the housing a bearing bracket mounted in the housing, a forming roll journaled in the bearing bracket, and means for vertically adjusting the bearing bracket in the housing. 95
17. A forming machine including a housing, two bearing brackets mounted therein, a pair of cylindric rolls mounted in one bearing bracket at an angle to each other, and a V-face roll journaled in the other bracket for operating in the angle of the cylindric rolls in co-operation with both of the same. 105
18. A forming machine including a housing, two bearing brackets mounted therein, a pair of cylindric rolls journaled in one bearing bracket at an angle to each other, a V-face roll journaled in the other bearing for operating in the angle of the cylindric rolls in co-operation with both of the same, and separate means for laterally adjusting the bearing brackets. 110
19. A forming machine including a housing, two bearing brackets mounted therein, a pair of cylindric rolls journaled in one bearing bracket at an angle to each other, a V-face roll journaled in the other bearing for operating in the angle of the cylindric rolls in co-operation with both of the same, and means for vertically adjusting one of the brackets. 115
20. A strip forming machine including successive sets of forming rolls on each side, the sets on one side being located opposite the intervals between the sets on the other 120 130

side, and supporting guides intervening between the sets of rolls on each side for guiding a partly formed strip from one set to another and co-operating with the intervening set on the opposite side of the machine.

21. A channel forming machine including web flattening rolls for delivering a formed channel, and an adjacent straightening roll having flanges engaging outside the channel

flanges and having tread portions bearing upon the edges of the flanges for deflecting the same upon the fulcrum formed by one of the flattening rolls.

In testimony that we claim the above, we have hereunto subscribed our names.

CARL A. FRAHM.
